UNITED STATES PATENT OFFICE.

FREDRICK MONROE BENWAY, OF MONTPELIER, VERMONT, ASSIGNOR TO PARKER WIRE GOODS COMPANY, OF WORCESTER, MASSACHUSETTS, A CORPORATION OF MASSACHUSETTS.

FRUIT-MARKER.

1,273,721.

Specification of Letters Patent. Patented July 23, 1918.

Application filed February 3, 1917. Serial No. 146,447.

To all whom it may concern:

Be it known that I, FREDRICK M. BENWAY, a citizen of the United States, residing at Montpelier, in the county of Washington and State of Vermont, have invented certain new and useful Improvements in Fruit-Markers; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in fruit markers or devices for holding tags giving price marks of fruits or other articles and consists of a simple and efficient device of this nature having various details of construction, combinations and arrangements of parts which will be hereinafter fully described, shown in the accompanying drawings and then specifically defined in the appended claim.

My invention is illustrated in the accompanying drawings, in which:—

Figure 1 is a front elevation.

Fig. 2 is a side view.

Fig. 3 is a top plan view.

Reference now being had to the details of the drawings by letter, A designates a wire bent to form a pyramidal shaped coil, said wire at the apex of the cone being bent to form a cylindrical coil upon edge, the folds

of which are in vertical planes and, being near together, form clamping means for the reception of a card D. Said device being of the shape shown may be conveniently placed over a pyramid of fruit or other articles for display purposes in windows, etc., and held thereby in proper position to display the card which is frictionally engaged between any two of the folds of the cylindrical portion of the holder.

It will be noted that by reason of the pyramidal shape of the convolutions the device frictionally engages the fruit or other spherically outlined object at different points, and with a plurality of convolutions so that the marker is held steadily upon the object without liability of being toppled over by the weight of the card.

What I claim to be new is:—

A fruit marker made of a single piece of wire bent to form concentrically disposed convolutions of pyramidal shape and adapted to engage frictionally with a plurality of its convolutions a spherically outlined object, a portion of the wire bent horizontally against the apex of the cone, thence vertically and formed into a horizontally disposed coil the lower edges of which are slightly above the top of the cone.

In testimony whereof I hereunto affix my signature in presence of two witnesses.

FREDRICK MONROE BENWAY.
